CLAIM

The ornamental design for a bottle with nozzle, as shown and described.

DESCRIPTION

FIG. 1 is a front, right side perspective view of a bottle with nozzle, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom view thereof.

The broken lines in the figures illustrate portions of the bottle with nozzle that form no part of the claimed design.
